UNITED STATES PATENT OFFICE.

ONESIME HEBERT, OF OKLAHOMA, OKLAHOMA, ASSIGNOR TO UNIVERSAL CAR AND HOSE COUPLER COMPANY, OF PHOENIX, ARIZONA, A CORPORATION.

COMBINATION CAR AND TRAIN-PIPE COUPLING.

1,426,732.

Specification of Letters Patent. Patented Aug. 22, 1922.

Application filed December 3, 1917. Serial No. 205,103.

To all whom it may concern:

Be it known that I, ONESIME HEBERT, a citizen of the United States, and a resident of Oklahoma city, in the county of Oklahoma and State of Oklahoma, have invented 5 certain new and useful Improvements in Combination Car and Train-Pipe Couplings, of which the following is a specification:

My invention relates to improvements in 10 draft appliances, consisting more particularly of the improvement in combination car and train pipe couplers disclosed in my application filed September 1, 1916, Serial Number 118103, and patented Dec. 28, 1920, 15 No. 1,362,973, and it consists in the constructions, combinations and arrangements herein described and claimed.

An object of my invention is to provide a 20 car and train pipe coupler which will simultaneously effect the automatic coupling of the train pipes with the coupling of the cars, and avoid the necessity of going between the cars.

Another object of the invention lies in 25 the provision of pipe blocks on each coupling head, in which the train pipes are so arranged that a tight compression joint will be formed between the pipes, upon coupling the heads together.

Other objects and advantages will appear 30 in the following specification, reference being had to the accompanying drawing, in which:

Figure 1 is a side elevation of a car coupling showing the arrangement of the pipe blocks.

Figure 2 is a vertical section of the parts shown in Figure 1.

Figure 3 is a detail cross section on the 40 line 3—3 of Figure 2, disclosing the arrangement of the coupling devices inside of the heads.

Figure 4 is an enlarged detail view of a portion of one of the pipe blocks.

Figure 5 is a vertical section taken substantially on the line 5—5 of Figure 4, and

Figure 6 is a detail view showing how the compression joint is formed.

In carrying out my invention I provide 50 the coupling heads 1 which contain features covered by another application. The essence of the present invention lies in the peculiar arrangement of the pipe blocks 31 carried by each coupling head. A brief description

of the principal structural features of the 55 coupling heads 1 in order to impart a clearer understanding of the relationship of the pipe blocks to the coupling heads, is thought to be of advantage.

Briefly then, the coupling heads 1 include 60 the knuckles 3 which are arranged to interlock with the companion coupling heads as shown in Figure 3. Each knuckle has a shoulder 4 which engages the edge of a lock opening 4^a in the companion coupling heads, 65 and the portion 4^b of the knuckle adjacent to the wall of the coupling is cut away to provide a wear compensating space. This space also enables the automatic maintenance of a constantly tight joint between the 70 train pipes. Dogs 24 operate to disengage the knuckles. The dogs 24 include short levers 26 by which the dogs are operated.

Each knuckle has an ear 7 which partly projects through an opening in the coupling head, and is mounted on a pin supported in ears 10 cast on the outside of the coupling head. Each head has a coupling pin 15 on which the end member 16 of a drawbar 19 is mounted. The drawbar is made in sections and has a spring 24 between the sections. The inter-engagement of the oppositely inclined surfaces of a bridge 17 on the members 16, with the inclined surfaces 18 of a recess in each head 1, keeps the head in 85 alignment with the drawbar.

Proceeding now, with the description of the invention, it should be observed that the lower end of each coupling pin 15 projects 90 beyond the bottom of the coupling head 1 as 15^a. This projection of the coupling pin forms an abutment for one end of a base 32 of the pipe block 31. The base 32 is an integral part of the pipe block, but it will be observed in Figure 4, that it extends a short 95 distance toward the rear, where it engages the abutment 15^a. The base is so shaped to form flanges 32^a at the sides as shown in Figure 5.

The flanges 32^a engage guides 30 cast 100 upon the bottom of the coupling head 1. The pipe block 31 is simply slid between the guides 30 until the projecting end of the base 32 engages the abutment 15^a. The pipe block 31 may be held in position either by 105 friction or some suitable device for fastening the pipe block to the coupling head.

Each pipe block 31 has one of more longi-

tudinal passages or bores 31^a, in which short pipe sections 33 are located. When the coupling is arranged to be used on passenger cars, the pipe block 31 is constructed for 5 three train pipes, but when the coupling is used on freight cars, the pipe block 31 is constructed for only a single train pipe. Each pipe section 33 extends a short distance beyond the ends of the pipe blocks. These 10 projecting ends of the pipe section are threaded to receive nuts 34.

The nuts 34 act as adjusting means for the pipe section, and also clamp it in place. When it is desired to adjust the pipe section, 15 one or the other of the nuts is loosened and the pipe section shifted accordingly. The nuts are then again tightened until they engage the ends of the pipe block as shown in Figure 4. A train pipe 35 is fastened to the 20 inner end of each pipe section 33 by a coupling 36.

A short piece of tubing or hose 37 is clamped on the outer projecting end of the pipe section 33, by a clamp 38. The hose 37 25 is longer than the projecting end of the pipe section. In other words, the end of the hose 37 normally extends slightly beyond the end of the projecting end of the pipe section, and forms a means for holding a gasket 39. These 30 normally extending portions are pressed together tightly when in the coupled position as in Figure 6.

The operation of the train pipe coupling will be clearly understood from the following, when taken in connection with the foregoing description. The hook 2 and knuckles 4 couple the heads 1 together when properly presented to each other. The adjustment of each of the pipe sections 33 in the pipe block 40 31 is such, that the projecting ends of each of the pieces of hose 37 will be tightly pressed together and the gasket 39 will be in such tight engagement that no fluid can escape. A tight compression joint is thus 45 automatically established. The ends of the hose pieces 37 will, of course, be first to engage when the heads 1 are coupled together. These projecting portions will thus be compressed longitudinally and spread radially. 50 The hose pieces are made of some flexible material as rubber, and it can readily be understood that when the action described takes place, the joint between the pipe sections will be very effective in retaining the 55 fluid in the pipe. The gaskets 39 are also

made of some slightly compressible material, so that the joint will be very tight.

In actual practice, the gaskets and the projecting ends of the hose pieces will be so arranged that the gaskets will not drop out. 60 The end of the hose piece is stretched to admit the gasket and thus holds the gasket in place.

While the construction and arrangement of the device as illustrated in the accompanying drawing is that of a generally preferred form, obviously modifications and changes may be made without departing from the spirit of the invention or the scope of the 65 claims.

I claim:

1. A car coupler head in combination with a detachable pipe block, the connections between said head and block comprising an open-ended way in one and a corresponding 75 tongue in the other whereby the pipe block may be engaged with the coupler head by a longitudinal movement, and a removable abutment on said head in contact with the rear of the pipe block adapted to resist rearward movement of said pipe block.

2. A car coupler head in combination with a detachable pipe block, the connections between said head and block comprising a way open at both ends in one and a tongue in the 85 other whereby the pipe block may be engaged with the coupler head by a longitudinal movement in either direction, and a removable abutment on said head arranged to engage the rear end of said block when 90 in place.

3. A car coupler head provided with a detachably mounted pipe block and a pin passing vertically through said head for connecting said head to a draw bar, said pin 95 serving also as an abutment for said pipe block.

4. A car coupler head in combination with a detachable pipe block, the connection between said head and block comprising an 100 open ended undercut way in one and a corresponding tongue in the other, whereby the pipe block may be engaged with the coupler head by a longitudinal movement, an abutment on said head against which the rear of 105 the pipe block is rigidly seated and which resists rearward movement of said pipe block.

ONESIME HEBERT.
